UNITED STATES PATENT OFFICE.

WILLIAM M. SCOTT, OF ELMWOOD, ILLINOIS.

PUMP.

SPECIFICATION forming part of Letters Patent No. 400,124, dated March 26, 1889.

Application filed January 14, 1888. Serial No. 260,794. (No model.)

To all whom it may concern:

Be it known that I, WILLIAM M. SCOTT, a citizen of the United States, residing at Elmwood, in the county of Peoria and State of Illinois, have invented a new and useful Pump, of which the following is a specification.

My invention relates to improvements in pumps having submerged cylinders; and the object of my improvements is to provide easy and speedy means of raising and lowering the cylinders without removing the discharge-pipe. I attain this object by the mechanism illustrated in the accompanying drawings, in which—

15 Figure 1 is a side view of the pump with parts cut away to show the valves. Fig. 2 is a back view showing pump partly raised, with parts cut away to show connection between pump and discharge-pipe. Fig. 3 is a cross-section drawn on the line N N. Fig. 4 shows the position of the lugs *d* and *c* when engaged.

Similar letters refer to similar parts throughout the several views.

25 A A' are pump-cylinders attached to bed-plate C.

D is a plate attached to discharge-pipe E, having openings K K', corresponding with openings in discharge-pipe E and with openings in cylinders A A'.

30 O O are flanges extending from the edges of bed-plate C, from which project lugs *c c*

c' c', forming a dovetail, in which the plate D fits.

d d d' d' are wedge-shaped lugs projecting from plate D and wedging against lugs *c c* 35 *c' c'* and holding bed-plate firmly against plate D when the pump is in position.

G G are spring-clamps extending from bed-plate around the discharge-pipe E and holding the pump to the pipe while raising or lowering the pump. 40

J J are ribs extending from discharge-pipe E and guiding the bed-plate C into position in lowering the pump.

H is a rod by which the pump is raised, lowered, or held in position. 45

What I claim as my invention, and wish to secure by Letters Patent, is—

In a pump, the combination of cylinders A A', attached to bed-plate C, a discharge-pipe, 50 E, a plate, D, attached to the discharge-pipe E, openings K K', connecting cylinders A A' and discharge-pipe E, lugs *d d d' d'* on plate D, lugs *c c c' c'* on bed-plate C, spring-clamps G G, attached to bed-plate C, projecting ribs 55 J J on discharge-pipe E, and a rod, H, attached to bed-plate C, substantially as set forth in foregoing drawings and specification.

WILLIAM M. SCOTT.
